(57) **CLAIM**

An ornamental design for an display screen with graphical user interface for radiotherapy machines, as shown and described.

DESCRIPTION

FIG. 1 illustrates a front view of an display screen with graphical user interface for radiotherapy machines, in accordance with a first embodiment of our design.

FIG. 2 illustrates a front view of an display screen with graphical user interface for radiotherapy machines, in accordance with a second embodiment of our design.

FIG. 3 illustrates a front view of an display screen with graphical user interface for radiotherapy machines, in accordance with a third embodiment of our design.

FIG. 4 illustrates a front view of an display screen with graphical user interface for radiotherapy machines, in accordance with a fourth embodiment of our design.

FIG. 5 illustrates a front view of an display screen with graphical user interface for radiotherapy machines, in accordance with a fifth embodiment of our design.

FIG. 6 illustrates a front view of an display screen with graphical user interface for radiotherapy machines, in accordance with a sixth embodiment of our design.

FIG. 7 illustrates a front view of an display screen with graphical user interface for radiotherapy machines, in accordance with a seventh embodiment of our design.

FIG. 8 illustrates a front view of an display screen with graphical user interface for radiotherapy machines, in accordance with an eighth embodiment of our design.

FIG. 9 illustrates a front view of an display screen with graphical user interface for radiotherapy machines, in accordance with a ninth embodiment of our design.

FIG. 10 illustrates a front view of an display screen with graphical user interface for radiotherapy machines, in accordance with a tenth embodiment of our design.

FIG. 11 illustrates a front view of an display screen with graphical user interface for radiotherapy machines, in accordance with an eleventh embodiment of our design.

FIG. 12 illustrates a front view of an display screen with graphical user interface for radiotherapy machines, in accordance with a twelfth embodiment of our design.

FIG. 13 illustrates a front view of an display screen with graphical user interface for radiotherapy machines, in accordance with a thirteenth embodiment of our design.

FIG. 14 illustrates a front view of an display screen with graphical user interface for radiotherapy machines, in accordance with a fourteenth embodiment of our design.

FIG. 15 illustrates a front view of an display screen with graphical user interface for radiotherapy machines, in accordance with a fifteenth embodiment of our design.

(Continued)

FIG. 16 illustrates a front view of an display screen with graphical user interface for radiotherapy machines, in accordance with a sixteenth embodiment of our design.

FIG. 17 illustrates a front view of an display screen with graphical user interface for radiotherapy machines, in accordance with a seventeenth embodiment of our design.

FIG. 18 illustrates a front view of an display screen with graphical user interface for radiotherapy machines, in accordance with an eighteenth embodiment of our design.

FIG. 19 illustrates a front view of an display screen with graphical user interface for radiotherapy machines, in accordance with a nineteenth embodiment of our design.

FIG. 20 illustrates a front view of an display screen with graphical user interface for radiotherapy machines, in accordance with a twentieth embodiment of our design.

FIG. 21 illustrates a front view of an display screen with graphical user interface for radiotherapy machines, in accordance with a twenty-first embodiment of our design.

FIG. 22 illustrates a front view of an display screen with graphical user interface for radiotherapy machines, in accordance with a twenty-second embodiment of our design; and, FIG. 23 illustrates a front view of an electronic device display screen with a graphical user interface, in accordance with a twenty-third embodiment of our design.

The broken line showing portions of the electronic device illustrates unclaimed environment and forms no part of the claimed design. The broken line showing portions of the graphical user interface illustrate unclaimed portions of the graphical user interface. The outer rectangular broken line in each drawing represents a display screen of an electronic device. The claimed graphical user interfaces are not intended to be limited to the scale illustrated in the figures.
